ELECTRON DISCHARGE DEVICE

Horst Rothe and Werner Kleen, Berlin, Germany, assignors to Telefunken Gesellschaft für Drahtlose Telegraphie m. b. H., Berlin, Germany, a corporation of Germany

Application September 18, 1936, Serial No. 101,380
In Germany October 8, 1935

8 Claims. (Cl. 250—27)

Our invention relates to electron discharge devices and particularly to such devices intended for use at high frequencies.

In the methods used at the present by the prior art for the control in amplifier tubes of electron currents, the electrons are influenced by the control field in a state wherein they have a relatively small velocity. This means that the electrons are for a relatively long time in the controlling alternating field. Also in transmitter tubes, cathode ray tubes and so forth, the control is effected in a zone of the discharge space wherein the electron speed is small. Special measures such as retarding electrodes have also been used in order 10 to render the electron speed within the control range equal to zero. This was due to the supposition that for the control of slowly moving electrons a small control potential was sufficient. However, the following relationships were not 15 taken into consideration: If the time of transit of the electrons approaches the duration of the period of the alternating potential impressed, the electrons will absorb energy from the coupled circuits connected to the electrodes, and that 20 there appears in these circuits attenuation phenomena which render the selective qualities poorer, that is, reduces the selectivity. For instance in high-frequency amplifier tubes, a loading of the tuned input circuit results.

The principal object of our invention is to provide an improved electron discharge device intended for use at high frequencies.

The invention is based upon the consideration that it is necessary for the elimination of the disadvantages above enumerated to render the time of transit of the electrons as short as possible in the control field. This is accomplished in accordance with the invention in that the electrons are influenced at such places where they still have 30 high velocity, in contrast to the method used by the prior art. Hence, in this manner, the influence of the controlling field on the individual electron lasts a very short time only and the result is that a detrimental attenuation of the control 35 circuit and a flattening out of its resonance curve is avoided.

The novel features which we believe to be characteristic of our invention are set forth with particularity in the appended claims, but the invention 40 itself will best be understood by reference to the following description taken in connection with the accompanying drawing in which Fig. 1 is a diagrammatic representation of an electrode system illustrating our invention; Fig. 2 shows 45 characteristic curves for the electrode system

shown in Fig. 1; Fig. 3 is a diagrammatic representation of an electron discharge device made according to our invention and Fig. 4 is a diagram illustrating one condition of operation of an electron discharge device made according to our invention. 5

The idea of the invention will now be explained with the aid of a few examples. In Fig. 1 the auxiliary electrodes are shown at I and I'. The control grid II of the amplifier tube has disposed 10 behind it the plate III. The potential of electrode I is designated by μ_1 , and the effective potential in the control grid area by μ_2 . The electrons enter the field existing between electrodes I and II at an angle of inclination α with respect to the 15 direction of the field. If this field is retarding, the electrons move on parabolic paths, as shown for instance by the dashes. A simple calculation shows that the electrons can only reach the control grid area II and thus also plate III if the 20 effective potential of the control grid area is

$$\mu_2 > \mu_1 \sin^2 \alpha \quad (1)$$

This formula points out that the velocity with which the electrons are retarded during the control action depends essentially on the size of angle α . If for instance, the electrons enter the field at angle α equal to zero, they must be retarded for the control down to zero speed. On the other hand, if it is assumed that angle $\alpha=45^\circ$ and that 25 the potential μ_1 of the auxiliary electrode I=100 volts, the apex of the parabolic electron paths is then located on a potential plane of about 50 volts. Hence, the electrons can reach the area of control grid II and plate III only when the 30 effective potential μ_2 of the control grid II is >50 volts and are then retarded only down to a speed of 50 volts in the direction in which they 35 are traveling. As long as the effective potential μ_2 of the control grid is <50 volts, the electrons 40 return to auxiliary electrode I, or they are taken up by auxiliary electrode I' whereby they are however again retarded only to 50 volts. 45

The discharge characteristic which results from electronic radiation composed of electrons of 50 equal speed and parallel direction, is shown in Fig. 2 by curve a. It may be seen, that the control takes place therefore with relatively high electronic speed and that the electrons do not stay very long in the control field. If the electron beam has a certain angular deviation $\Delta\alpha$ at the entrance in the retarding field, the characteristic assumes the form of curve b in Fig. 2. This is due to the fact that to the electrons entering the control field under different angles 55

there must be coordinated effective potentials of different size at the control grid in order to cause them to return. The rounding of the characteristic takes place between the potential values

$$\mu_2 = \mu_1 \sin^2(\alpha \pm \Delta\alpha) \quad (2)$$

The form of characteristic shown in Fig. 2 is entirely novel, for in all characteristics known up to the present in the prior art the discharge current starts with the effective potential 0 of the control grid. Hence these characteristics are evolved under the assumption that the control influences those electrons which are retarded down to very small speeds. The characteristics shown in Fig. 2 start only with positive effective potentials and move the more in the direction of positive effective potentials the larger is chosen the angle of incidence α , that is the faster the electrons that are used where they are turned back.

As shown by Formula 1, there exists a relationship between the size of the effective potential μ_2 at the control grid electrode required for the control of the electron beam and the angle of incidence α of the electron rays. From this it may be seen that the control can be accomplished by variation of the intensity of the controlling field, as well as by influencing the effective potential μ_2 , or then again by variation of angle α . In certain cases the simultaneous use of both controls might come in consideration. In both cases the means known for intensity control or angular control of discharge currents may be employed, for angular control magnetic as well as electrostatic deflection fields can be brought to act.

The electrode arrangement shown in diagrammatic manner in Fig. 1 is solely to serve for an explanation of the idea of the invention. Fig. 3 shows the cross-section through an electrode system suitable for the practical application of the idea of the invention. From the hot cathode K electrons move through grid-like electrode 1 (potential μ_1) outwards and are parted into two bundles or beams, B, B' by rods 3 charged with cathode potential. If for instance electrode 5 is also impressed with the potential μ_1 a characteristic is obtained with the variation of the potential of electrode 4 whose course coincides with the one of the characteristics b of Fig. 2. The electron current is distributed in this case between electrodes 4 and 5. The steepness of the characteristic depends on the size of the angle of divergence with which the electrons enter the retarding field of the control space.

If it is desired to make the steepness of the discharge characteristic as great as possible it is necessary to make this angle of divergence which was given the symbol $\Delta\alpha$ previously as small as possible. To achieve this there are basically two possibilities:

1. The electrons are sharply focused into beams so that the electrons move in parallel paths and enter a homogeneous decelerating field at a definite angle α of definite sense.
2. With insufficient focusing of the beam, that is where the electrons leave the cathode in various directions and move therefore in diverging paths, the retarding field can be shaped so that all electrons enter the field at the same angle.

The second case is shown in Fig. 4. Here the electrons of various courses enter a decelerating field of such curvature that they pass through the same equi-potential area P, P', P'' at the

same angle α . This again has the result that the electrons return on the same potential area, practically speaking, that is reach the control area with the effective potential of the latter being equal for all electrons and thus they reach the anode.

While we have indicated the preferred embodiments of our invention of which we are now aware and have also indicated only one specific application for which our invention may be employed, it will be apparent that our invention is by no means limited to the exact forms illustrated or the use indicated, but that many variations may be made in the particular structure used and the purpose for which it is employed without departing from the scope of our invention as set forth in the appended claims.

What we claim as new is:—

1. The method of controlling a discharge current in an electron discharge device having a source of electrons, control electrodes and an anode, and comprising establishing an electric control field between said control electrodes and said anode a portion of said field having a retarding characteristic, applying an alternating potential to one of said control electrodes, and causing electrons to pass through said electric control field at an angle with respect to the direction of the field in a period of time small compared to the period of said alternating potential. 30

2. The method of controlling a discharge current in an electron discharge device having a source of electrons, control electrodes and an anode, and comprising establishing an electric control field between said control electrodes and said anode, applying an alternating potential to one of said control electrodes, and causing electrons to enter said electric control field at an angle with respect to the direction of the field and to pass through said electric control field in a period of time small compared to the period of said alternating potential. 35

3. The method of controlling a discharge current in an electron discharge device having a source of electrons, control electrodes and an anode, and comprising establishing an electric control field between said control electrodes and said anode a portion of said field having a retarding characteristic, applying an alternating potential to one of said control electrodes, and causing electrons to pass through said electric control field at an angle with respect to the direction of said field in a period of time small compared to the period of said alternating potential, and controlling said electrons by varying the intensity of the electric control field. 55

4. The method of controlling a discharge current in an electron discharge device having a source of electrons, control electrodes and an anode, and comprising establishing an electric control field between said control electrodes and said anode, applying an alternating potential to one of said control electrodes, and causing electrons to pass through said electric control field, and controlling said electrons by varying the angle of incidence between said electrons and the direction of the electric control field to cause said electrons to pass through said electric control field in a period of time small compared to the period of said alternating potential. 60

5. The method of controlling a discharge current in an electron discharge device having a source of electrons, control electrodes and an anode, and comprising establishing an electric control field between said control electrodes and 70

5 said anode, applying an alternating potential to one of said control electrodes, and causing electrons to pass through said electric control field at an angle to the direction of the field and simultaneously varying the intensity of the control field and the angle of incidence between the electrons and the control field to cause said electrons to pass through said electric control field in a period of time small compared to the period of 10 said alternating potential.

10 6. The method of controlling a discharge current in an electron discharge device having a source of electrons, control electrodes and an anode, and comprising establishing an electric control field between said control electrodes and said anode, applying an alternating potential to one of said control electrodes, and causing said electrons to enter the electric control field so that 15 all the electron paths pass through co-equivalent equipotential areas of the electric control field at the same angle but differing from 90°.

20 7. The method of controlling a discharge current in an electron discharge device having a

source of electrons, control electrodes and an anode, and comprising establishing homogeneous electric control field between said control electrodes and said anode, applying an alternating potential to one of said control electrodes, and focusing said electrons into concentrated beams 5 to pass through said homogeneous control field.

8. The method of controlling a discharge current in an electron discharge device having a source of electrons, control electrodes and an anode, and comprising establishing an electric control field between the control electrodes and the anode, applying an alternating potential to one of said control electrodes and causing said electrons to enter said electric control field in diverging paths and forming said electric control field so that the potential areas are curved to cause all the electron paths to pass through equivalent equipotential areas at the same angle 15 but differing from 90°. 20
